ROTARY FLUID MOTOR

Mart C. Perkins, Casper, Wyo.

Application August 25, 1937, Serial No. 160,924

2 Claims. (Cl. 121—71)

This invention relates to rotary engines and more particularly to an improved construction of a rotary motor of the fluid type.

One object of this invention is to provide a new and improved construction of a rotary engine. Another object of this invention is to provide an improved fluid control system for a rotary engine. A further object of this invention is to arrange a rotary engine with its pistons and gear drives all within a unitary housing. Other objects and advantages of this invention will appear in the following description taken in connection with the accompanying drawings.

Figure 1 is a vertical cross section showing the arrangement of the cylinders and abutments. Figure 2 is a fragmentary end elevation of one end of the engine. Figure 2a is a fragmentary end elevation of the opposite end of the engine. Figure 3 is a vertical section taken substantially through the center of the engine. Figure 4 is a transverse cross section of the piston corresponding to a section on line 4—4 of Figure 1. Figure 5 is an enlarged view showing the piston in greater detail. Figure 6 is a view of the power fluid valve viewed on the line 6—6 of Figure 7. Figure 7 is an enlarged view substantially on the line 7—7 of Figure 1. Figure 8 is a detail of the lubricating system.

The engine comprises a housing 10 having a toroidal cylinder 11 in the inner circumference 12 of which is rotatably mounted a ring gear or rotor 13. The ring gear or rotor 13 carries upon its periphery a plurality of pistons or vanes 14. At spaced points about the cylinder are located rotary abutments 15 each of which is recessed as at 16. The remainder of the periphery of each abutment is provided with a plurality of gear teeth 17 which mesh with gear teeth 18 of the ring gear. In operation the ring gear rotates in a counterclockwise direction as viewed in Figure 1 carrying with it the pistons 14 which are forced around through the toroidal cylinder by the power fluid and which nest successively within or pass through the respective recesses 16 of each abutment during the rotation of the engine.

Steam, compressed air or some other power fluid is admitted to the power fluid inlet box 19 by means of the inlet ports 20. The disc valve 21 rotates about its shaft 22 to an appropriate point where the elongated arcuate port 23 places the steam box or power fluid supply means 19 in communication with the port 24, which in turn is in communication with the cylinder 25 in which the abutment rotates through recess 16 at the

time the piston 14 is passing out of the recess 16. Steam or other power fluid enters the cylinder through the space provided by the recess 16 of the rotary abutment and continues to fill up the space in the cylinder limited by the abutment at one end and the trailing face 26 of the piston 14 at the other end. The pitch circles of the gear teeth 17 on the abutment and 18 on the ring gear are so arranged that the pistons will successively engage the recess of each abutment. The continued movement of the abutment in a clockwise direction cuts off the admission of steam and the expansion of the steam in the cylinder 11 moves the piston 14 away from the abutment A toward the abutment B. When the piston clears the exhaust port 27, the expanded steam is released from the cylinder thereby allowing the piston to pass through the recess 16 of abutment B so that the cylinder will then receive a new supply of steam from the corresponding ports of abutment B and the piston will again be forced in a counterclockwise direction towards the abutment C during which the cycle of operation is repeated. This same action takes place behind each piston and between each piston and abutment which it has just passed. In this manner a continuous series of power impulses are applied to the pistons which transmit the power in turn to the ring gear 13, which in turn transmits the power impulses to shaft 28 by means of a keyed driving connection 29. The number of teeth 18 on the ring gear is properly coordinated with the number of teeth on the periphery of the rotary abutment so that each piston will ride through the abutment recess as it passes the abutment. The opposed faces 26 and 30 of each piston are arranged with a contour corresponding to a tooth curve so that an accurate intermeshing of the piston and the abutment recess will be obtained.

The housing is preferably made in the form of opposed segments 31 and 32 providing the cylinder space for the rotary abutment and a segmental portion of the toroidal cylinder for the pistons. These portions of the housing are bolted together by appropriate securing means 33 and to that side portion of the housing in which the rotary abutment is mounted is secured by means 34 the power fluid supply means 19. For the purpose of simplifying and improving the engine the steam valve 21 and the abutment 15 are keyed to a shaft 22 at the points 35 and 36 respectively. In this manner the steam valve cooperates with the abutment to provide for the necessary inlet of the power medium. To operate the abutments 55

and the steam valves in a properly co-ordinated manner with respect to the pistons, geared connections are provided between the ring gear and the abutments. These driving connections are all interiorly of the housing so that an auxiliary housing is not needed for the driving connections.

The pistons are preferably secured upon arms 37 equi-distantly spaced about the periphery of the ring gear. Each piston comprises a segment 10 of a toroid formed by two complementary truncated tubular members 38 and 39. The abutting surfaces 40 and 41 contain complementary portions forming an annular slot 42 in which is positioned a piston ring 43. The piston is assembled 15 with the piston pin 44 projecting through the side walls 45 of the piston but terminating interiorly of the ring as at 46 in Figure 4, the pin passing through the opening 47 of the arm 37 giving the driving connection to the ring gear. 20 When the elements have all been assembled, they are appropriately secured together by means of a rivet 48.

In an engine of this type it is obviously necessary to provide appropriate lubrication and this 25 is accomplished by a system now to be described. The entire housing of the engine is mounted upon supports 49 and the central portion of the housing is sealed by end members 50 and 51. These members provide appropriate bearing portions 52 and 30 53 for the shaft and are in turn reinforced by a series of radial ribs 54 and 55. These members also enclose the ring gear within the housing. On the left end member 51 an annular flange 56 together with the sealing member 51 provides an 35 oil reservoir and an appropriate housing for the reciprocating lubricating pump 58. The bottom of this housing contains a body of lubricant 59 which is taken into the pump 58 by means of its inlet 60 and forced into the bearing system by the 40 tube 61. This latter tube is in communication with an annular oil groove 62 and shaft and by means of radial passages 63 is placed in communication with an axially extending oil passage 64. The latter communicates with the various 45 oil grooves 65, 66 and 67. The oil groove 66 has further communication with an oil passage 67 passing through one or more of the spokes 68 of the ring gear and is placed in communication with the friction surfaces between the abutment 50 and the housing at the point 71. This also supplies lubricant to the intermeshing gear teeth in the neighborhood of the point 72. Lubrication for the bearings, rotary abutment and steam valve is provided by means of a series of tubes 55 73 carrying oil from the oil channel 67 to the center of the shaft 22. The latter shaft contains a central bore which is in communication with the bearings 75 and 76. It will be readily appreciated that the pump 58 maintains a continuous 60 supply of lubricant as a result of the rotation of shaft 28. This is accomplished by the cam 71 which is keyed to the shaft 28 by means of the key 78 which is either a direct connection from a cam wheel 77 or which may be a connection by means of a collar which in turn carries the cam. The rotation of the cam 71 forces the plunger 80 in a radial direction against the opposition of the spring 81 and accomplishes the necessary operation of the pump 58.

70 The supply of oil in the system may be maintained by occasionally replenishing it through port 82. Loss of oil along the shaft is avoided

by packings 83 secured in place by the packing rings 84. The plate 50 is secured to the housing by a series of bolts 85 and the plate 51 is secured to the housing by a series of bolts 86. The cover member 57 is secured in place to seal the reservoir by a series of bolts 87.

The abutments may be provided with counter-balance means such as bore holes if necessary to smooth out the rotary motion. To make the operation of the engine more efficient bleed lines 10 88 to 91 are placed about a portion of the periphery of the abutment so that any power fluid trapped in the pocket 16 can escape and be useful on the piston. This cannot occur by the tooth groove 92. The gear member 13 is provided with 15 laterally projecting cylindrical shoulders 94 on opposite sides thereof which rotatably engage in a cylindrical bore 95 and the teeth 18 of the gear 13 engage in an annular slot 93 provided on the inner side of the cylinder 11.

Although a preferred embodiment of this invention has been shown and described, variations coming within the true spirit and scope of the invention are to be determined by the appended claims.

What I claim is:

1. A rotary engine comprising a housing having a ring-shaped cylinder therein provided with an annular slot on the inner side thereof, a shaft disposed axially of said cylinder, a gear secured 30 to said shaft within said housing having the teeth thereof engaging within said annular slot, a plurality of circumferentially spaced apart pistons secured to said gear and engaging within said cylinder, said housing having a plurality of circumferentially spaced apart abutment chambers communicating with said cylinder, an abutment shaft journaled through each chamber, an annular abutment in each chamber fixed to an abutment shaft and projecting interiorly of said cylinder, 40 each abutment having a peripheral recess to receive a piston, a valve chamber extending laterally of and communicating with each abutment chamber, a rotary inlet valve in each valve chamber fixed to an abutment shaft, gear teeth carried 45 by each abutment engaging said first gear, said cylinder having an exhaust port between each abutment chamber.

2. A rotary engine comprising a housing having a ring-shaped cylinder therein provided with 50 an annular slot on the inner side thereof, a shaft disposed axially of said cylinder, a gear secured to said shaft within said housing engaging in the slot thereof, laterally projecting cylindrical shoulders carried by said gear, a plurality of circumferentially spaced apart pistons secured to said gear and engaging within said cylinder, said housing having a plurality of circumferentially spaced apart abutment chambers communicating with said cylinder, an abutment shaft journaled 60 through each chamber, an annular abutment in each chamber fixed to an abutment shaft and projecting interiorly of said cylinder, each abutment having a peripheral recess to receive a piston, a valve chamber extending laterally of 65 and communicating with each abutment chamber, a rotary inlet valve in each valve chamber fixed to an abutment shaft, gear teeth carried by each abutment engaging said first gear, said cylinder having an exhaust port between each 70 abutment chamber.

MART C. PERKINS.
